CARBURETER

1,290,508.

Specification of Letters Patent.

Patented Jan. 7, 1919.

Application filed October 4, 1915. Serial No. 53,899.

To all whom it may concern:

Be it known that I, AQUILA D. CHANDLER, a citizen of the United States, residing at Chicago, in the county of Cook and State 5 of Illinois, have invented a certain new and useful Improvement in Carbureters, of which the following is a full, clear, concise, and exact description, reference being had to the accompanying drawings, forming 10 a part of this specification.

My invention relates to the art of carburetion and contemplates an improved carbureter for association with internal combustion engines.

15 It is the object of my invention to provide a carbureter that is durable, capable of being cheaply constructed, and one wherein the most efficient mixtures are produced and supplied to the engine for the various engine speeds. In the operation of my hereinafter described carbureter the constituent proportions of the combustible mixture supplied to the internal combustion engine with which the carbureter is associated are determined, maintained and graded automatically 20 and without adjustment other than that necessary preliminarily.

The carbureter of my invention affords a number of advantages among which may 25 well be mentioned the fact that the carbureter is capable of automatically adapting itself to the requirements of its associated engine and thus supply the proper mixture to the engine for all speeds thereof and so 30 does away with "choking" the engine by loading it with a too rich mixture as is often the case when ordinary carbureters are used, when with the engine throttle down the throttle valve is rather suddenly opened to 35 a greater or less extent.

A further important advantage of the carbureter of my invention resides in the fact that under running conditions a comparatively low vacuum of small range is maintained within the engine manifold and carbureter mixing chamber. Due to this fact each of the engine pistons during almost the entire length of each of its suction strokes serves to draw combustible mixture 45 into its associated cylinder thus enabling me to secure higher compression with a consequent increase in power. In other words, it has been my experience that when many carbureters of the prior art are used a considerable portion of the suction stroke of 50 each engine piston is utilized to reduce the

pressure within its associated cylinder to a degree less than the pressure in the manifold and carbureter and thus but a comparatively small portion of each piston suction stroke 60 is utilized to draw combustible mixture into the engine cylinder. When my improved carbureter is made use of this disadvantage inherent in the prior art carbureters is obviated.

65

In so far as the present embodiment of my invention is concerned the abovementioned and other advantages to be herein-after enumerated are obtained by a construction wherein all of the moving parts with 70 the exception of the spring pressed auxiliary air valve are mechanically connected with the manually operated throttle and are operated synchronously therewith.

My invention is illustrated in the accompanying drawings wherein,

Figure 1 is a top plan view of my improved carbureter.

Fig. 2 is a view partly in section and partly in elevation taken on a vertical plane 80 through the line 2-2 of Fig. 1 and looking in the direction indicated by the arrows.

Fig. 3 is a vertical sectional view taken on the line 3-3 of Fig. 1 and looking in the direction indicated by the arrows; and 85

Fig. 4 is an isolated detail view in section of the auxiliary air valve taken on the line 4-4 of Fig. 1 and looking in the direction indicated by the arrows.

Similar characters of reference refer to 90 similar parts throughout the several views.

The carbureter casing is illustrated at 5 and it will be seen that it provides a carbureting chamber 6 with which communicates a main air inlet passage 7 and a mixture outlet at 8. A flange 9 encircles the outlet 8 so that the carbureter may be attached to the manifold 10 of an internal combustion engine in the usual manner. The casing 5 is conformed to provide a seat 95 for the upper edge of a cup 11 which is retained in position by a nut 12 threaded upon the lower end of the downwardly extending portion 5a of the carbureter casing. It will be seen that the cup 11 is disposed 100 co-axially with the carbureting chamber 6 and that the aforesaid cup 11 constitutes a constant level fuel chamber, commonly known as the float chamber. The float, 105 illustrated at 13, which in the present embodiment of my invention is of the annular type, co-operates with mechanism of any 110

suitable construction (not shown) to maintain the liquid fuel within the float chamber at a substantially constant level in a well known manner.

5 In the present embodiment of my invention the novel features characterizing my invention are utilized in connection with a carbureter of the puddle type and, therefore, the extension 5^a of the carbureter casting is conformed to provide a puddle chamber 14 communicating at its lower end with the float chamber. A normally closed petcock 15 is conveniently provided to drain the fuel from the float chamber and the puddle chamber 14 when this becomes desirable.

10 The passage between the puddle chamber 14 and the float chamber is regulated by means of a needle valve 16 which, at its upper end has threaded engagement with the cap 17 of the carbureting chamber 6 and is, moreover, provided with a knurled hand piece 18 to facilitate adjustment of the needle valve. The lower end of the needle valve 16 extends through a sleeve 19 supported through a spider from the lining 20 of the puddle chamber 14. It will be seen that the lower end of the sleeve 19 terminates in the puddle chamber 14 below the normal lever of the fuel within the 25 float chamber and that inasmuch as there is an annular space between the sleeve 19 and the needle valve the sleeve 19 under certain operating conditions serves to provide a conduit for liquid fuel from the 30 puddle chamber 14.

35 Suspended in the carbureting chamber 6, and conveniently retained in position by a split ring 21 coöperating with a groove in the wall of the carbureting chamber is the venturi 22.

40 As thus far described the present embodiment of my invention does not differ in any material respect from the ordinary puddle carbureter commonly in use and with 45 which all persons skilled in the art of carburation are familiar. It will be understood, therefore, that numerous changes may be made in the detailed construction of these features of the carbureter at the 50 same time securing the mode of operation and result which characterize my present invention.

55 Disposed in the mixture outlet 8 at a point somewhat removed from the flange 9 is a throttle in the form of a butterfly valve 23 mounted upon a shaft 23' journaled in the carbureter casing 5, as is most clearly illustrated in Fig. 3. Fixed with respect to the upper end of the shaft 23' 60 are the three arms 24, 25, and 26. The arm 24 serves as a crank arranged to be connected with the usual controlling rod whereby the position of the throttle valve 23 may be manually controlled from any 65 convenient point, as, for instance, the steer-

ing column or dash of an automobile of which the carbureter and its associated engine form a part. The arm 25 is provided with an adjustable screw 27 which engages a lug 28 formed on the cap 17 of the carbureting chamber when the throttle valve 23 is in closed position. Disposed within the air inlet passage 7 is a butterfly valve 29 mounted upon a shaft 30 journaled in the carbureter casing, the upper end of said shaft 30 having attached thereto a lever 31 the free end of which is connected through a link 32 with the free end of the arm 26 which, as has been previously explained, has the other end thereof fixed with respect 80 to the upper end of the shaft 23' upon which the butterfly valve 23, or throttle, is mounted. The connection between the butterfly valves 23 and 29 is such that these valves are operated simultaneously and to 85 the same extent when the crank 24 is operated through its controlling mechanism (not shown).

90 As is perhaps most clearly illustrated in Figs. 1 and 2, the carbureter casing provides a conduit 33 for the passage of auxiliary air, this conduit 33 being controlled at its intake end by a spring controlled puppet valve 34 coöperating with a seat 35 threaded upon the carbureter casing 5, as illustrated 95 in Fig. 4, the seat 35 conveniently having formed integral therewith a spider and a sleeve 35^a through which extends the stem 36 of the puppet valve. Threaded upon the upper end of the stem 36 is a nut 37 for 100 adjusting the tension of the spring 38 which normally retains the valve 34 in seated position. It will be understood that the valve 34 may be of any conventional construction and need not necessarily be of the precise 105 type illustrated in the drawing. The outlet end of the conduit 33 for auxiliary air terminates in the mixture outlet passage 8 at a point intermediate the butterfly or throttle valve 23 and the engine manifold. 110 It will, therefore, be seen that the operation of the puppet valve 34 is wholly controlled by the partial vacuum created within the engine manifold and that the operation of the valve 34 is unaffected by the throttle 115 valve 23 except in so far as the position of the throttle valve 23 affects the pressure within the engine manifold. The response of the auxiliary air valve 34 to partial vacuums created within the manifold is 120 regulated and determined by a butterfly valve 39 mounted upon a shaft 40 and located in the conduit 33 at a point intermediate the auxiliary air valve 34 and the mixture outlet 8. Fixed to the upper end 125 of the valve shaft 40, as is most clearly illustrated in Fig. 1, is a lever 41 connected by a link 42 with the arm 26 which, as has been previously pointed out, is fixed with respect to the shaft 23' upon which the but- 130

terfly throttle valve 23 is mounted. The arrangement is such that the butterfly valve 39 is operated simultaneously with the throttle valve 23 in substantially the same manner as is the butterfly valve 29 located in the air inlet passage 7.

As most clearly illustrated in Figs. 1 and 2, a passage 43 is formed in the carbureter casing, this passage leading from the puddle chamber 14 below the normal fuel level therein to the mixture outlet passage 8 at a point intermediate the throttle valve 23 and the engine manifold. It will be understood that this passage 43 serves to permit the passage of fuel from the puddle chamber 14 to the mixture outlet 8 during the operation of starting the engine in order to afford the rich mixture necessary to the starting operation.

I find that by providing the arrangement previously described a comparatively low vacuum of comparatively small range is maintained within the carbureting chamber 6 and the Venturi tube during normal running conditions, the auxiliary air valve 34 being adjusted to respond to admit auxiliary air when the engine speeds up and thus tends to increase the vacuum within the engine manifold and the carbureting chamber.

The fact that a low and substantially constant vacuum is maintained within the engine manifold and carbureting chamber during ordinary running conditions is a matter of considerable importance, as has been previously pointed out, inasmuch as when this condition exists greater compression, with a consequent increase in power developed by the associated engine, is assured.

It will be seen that the butterfly valve 39 serves to prevent what might otherwise be the effect of the air valve 34 at low engine speeds. I may point out at this time that I find the butterfly valve 39 may in some cases be arranged to close slightly before the throttle valve 23 is closed, this arrangement being for the purpose of permitting the engine to be readily started, but the difference in the position of the two valves in such a case is so slight that the operation of the carbureter is identical at the higher-engine speeds with the operation of the carbureter when all of the butterfly valves are simultaneously opened and closed.

As has been previously pointed out, the carbureter construction herein described successfully prevents the engine from being loaded with a too rich mixture in case the throttle valve be quickly moved from nearly closed position to fully open or nearly fully open position. If it were not for the novel arrangement which I provide for supplying the carbureter with auxiliary air the tendency in such a case would be to supply the engine with a very rich mixture in a

considerable quantity. If the engine in such case were to be running at comparatively low speed when the throttle was thus suddenly opened the engine would be unable to handle the large quantity of rich mixture and would become overloaded with mixture and choke, as I have previously pointed out.

Having thus described the carbureter of my invention what I claim as new and desire to secure by Letters Patent of the United States is:

1. In combination with a carbureting chamber having an air inlet and a mixture outlet arranged to be connected with an internal combustion engine, a throttle valve in said mixture outlet, an auxiliary air inlet communicating with the mixture outlet intermediate the throttle valve and the engine, a check valve controlling the admission of air to said auxiliary air inlet, a valve in the first-mentioned air inlet, devices for insuring the simultaneous and similar operation of said last-mentioned valve and said throttle valve, and means mechanically connected with said throttle valve for limiting the admission of air through said check valve.

2. In combination with a carbureting chamber having an air inlet and a mixture outlet arranged to be connected with an engine, a throttle valve in said mixture outlet, an auxiliary air inlet communicating with the mixture outlet intermediate the throttle valve and the engine, a check valve controlling the admission of air to said auxiliary air inlet, a valve in the auxiliary air inlet controlling communication with the mixture outlet, and devices for insuring simultaneous and similar operation of said last-mentioned valve and said throttle valve.

3. In combination with a carbureting chamber having an air inlet and a mixture outlet, a constant level fuel supply chamber, a puddle in the carbureting chamber communicating with the fuel supply chamber, a throttle valve in the mixture outlet, a passage leading from the puddle to the mixture outlet at a point intermediate the throttle and the engine, an auxiliary air inlet communicating with the mixture outlet intermediate the throttle and the engine, a check valve controlling the admission of air to said auxiliary air inlet, a manually operable valve in the first-mentioned air inlet, a manually operable valve in the auxiliary air inlet controlling communication with the mixture outlet, and means for operating said manually operable valves simultaneously with the throttle valve.

4. In combination with a carbureting chamber having an air inlet and a mixture outlet, a constant level fuel supply chamber, a puddle in the carbureting chamber communicating with the fuel supply chamber, a throttle valve in the mixture outlet, a passage leading from the puddle to the

4
mixture outlet at a point intermediate the throttle and the engine, an auxiliary air inlet communicating with the mixture outlet intermediate the throttle and the engine,
5 a check valve controlling the admission of air to said auxiliary air inlet, a valve in the auxiliary air inlet controlling communication with the mixture outlet, and means for operating said last-mentioned valve si-
10 multaneously with and similarly to the throttle valve.

5. In a carbureter for internal combustion engines, the combination with a carbureting chamber having an air inlet, a
15 combustible mixture outlet, a throttle valve in the combustible mixture outlet, an auxiliary air inlet communicating with the combustible mixture outlet intermediate the throttle valve and the engine, an adjustable
20 valve in said auxiliary air inlet and mechanism connected with said throttle valve for adjusting said valve, and means for automatically regulating the supply of air through said auxiliary air inlet.

25 6. In a carbureter for internal combustion engines the combination with a carbureting chamber having an air inlet, a combustible mixture outlet, a throttle valve in the mixture outlet, an auxiliary air inlet
30 communicating with the combustible mixture outlet intermediate the throttle valve and the engine, a normally closed automatic valve at the intake end of said auxiliary air inlet, an adjustable butterfly valve located
35 in said auxiliary air inlet, and mechanism connected with said throttle valve for adjusting said butterfly valve.

7. In a carbureter, the combination with a carbureting chamber having an air inlet
40 and a mixture outlet, of a throttle valve in

the mixture outlet, a valve in the air inlet, means for insuring similar and simultaneous operation of said last-mentioned valve and said throttle valve, an auxiliary air inlet communicating with the mixture outlet intermediate the throttle valve and the associated engine, automatic means for regulating the supply of air through said auxiliary air inlet, and means operably connected with said throttle valve for regulating the supply of air through said auxiliary air inlet.

8. In a carbureter the combination with a carbureting chamber having an air inlet and a mixture outlet arranged to be connected with an engine, a throttle valve in the mixture outlet, an auxiliary air inlet passage communicating with the mixture outlet intermediate the throttle and the engine, a valve in the auxiliary air inlet pas-
55 sage, devices connecting said last mentioned valve and said throttle valve whereby said valves are operated from the same operating mechanism, and an inwardly opening check valve in said auxiliary air inlet pas-
60 sage.

9. An inlet device of the specified class, comprising an air conduit, a compensating valve therein, a throttle between the compensating valve and the intake manifold, a throttle between the source of gas supply and the manifold, and means for connecting and operating the throttles together.

In witness whereof, I hereunto subscribe my name this 2nd day of October, A. D. 75
1915.

AQUILA D. CHANDLER.
